BATHROBE PACKAGE AND THE LIKE

Filed April 13, 1928

UNITED STATES PATENT OFFICE

SAMUEL HOROWITZ, OF NEW YORK, N. Y., ASSIGNOR TO ROYAL ROBES CO., INC., OF NEW YORK, N. Y., A CORPORATION OF NEW YORK

BATH-ROBE PACKAGE AND THE LIKE

Application filed April 13, 1928. Serial No. 269,855.

My present invention relates to boxes or like containers, especially such as are adapted for use with bathrobes or bathrobe and slippers combinations, and aims to devise 5 containers for the general purposes designated, which are simple in construction, which may be readily and economically fabricated and assembled and which are highly suitable for the general purposes indicated 10 and are very satisfactory in use. Other objects and advantages of the devices of the present invention will in part be pointed out in detail hereinafter and will in part be obvious to those skilled in the art to which the 15 present invention relates.

In the accompanying specification I shall describe and in the annexed drawing show an illustrative embodiment of the devices of the present invention. It is, however, to be 20 clearly understood that my invention is not restricted to the specific embodiment thereof, herein shown and described for purposes of illustration only.

Referring to the drawing, wherein I have 25 shown the aforesaid illustrative embodiment of the present invention:

Fig. 1 is a plan view of the container portion of a box or like receptacle, constituting a portion of the aforesaid illustrative embodiment of the devices of the present invention;

Fig. 2 is a cross-sectional view of the same, taken along 2-2 of Fig. 1 of the drawing;

Fig. 3 is a longitudinal sectional view of 35 the same, taken along 3-3 of Fig. 3 of the drawing;

Fig. 4 is a plan view of a blank for the member constituting the main retaining and reenforcing means forming a part of the 40 aforesaid illustrative embodiment of the devices of the present invention; and

Fig. 5 is a plan view of a blank for the member constituting the auxiliary retaining and reenforcement means forming a part of the 45 aforesaid illustrative embodiment of the devices of the present invention.

Referring to the aforesaid illustrative embodiment of the devices of the present invention and with particular reference to the 50 drawing illustrating the same, 10 indicates

generally the container or lower portion of a box or receptacle for containing a bathrobe or bathrobe and slippers combination, preferably the latter, the cover being omitted, since it is of the usual construction and 55 need not therefore be either illustrated or further described here. The box 10 comprises the main or bathrobe portion 11 and the auxiliary or slippers portion 12. I prefer that the sides 13 and 14 and the ends 15 and 16 of the box 10 shall be doubled or two-ply, as by being folded over, in a manner which will be readily apparent to those skilled in the art to which the present invention relates. The outer plies or folds of 60 the sides 13 and 14 and the ends 15 and 16 have been designated by reference characters 13', 14', 15' and 16', respectively, while the inner plies or folds of such sides and ends have been designated by reference characters 70 13'', 14'', 15'' and 16''.

Separating the auxiliary or slippers portion 12 of the box from the main or bathrobe portion 11 of the box is a partition 20, which may similarly be made of two-ply or 75 folded material, the one ply being designated by reference character 20' and the other ply by reference character 20''. It may here be stated that the box 10 may be made of various types of material, generally 80 of a fairly pliable cardboard or the like, from which such boxes are customarily made.

I provide the main or bathrobe portion 11 of the box 10 with combined retaining and 85 reenforcing means, for the purpose of retaining securely and neatly in place the bathrobe, generally designated by reference character 30. For this purpose, I may employ a combined retaining and reenforcing member made of a blank such as that illustrated in Fig. 4 of the drawing, where the blank has been generally designated by reference character 40. The blank 40 comprises a central web portion 41 and the tab portions 42 and 43 at the ends of the web portion 41. The tab 42 constitutes a main tab portion which may have any desired shape, but is preferably substantially rectangular, so as to render relatively difficult 90 95 100

its removal from the portion of the box structure into which it is inserted, as will shortly be described. The tab 43, on the other hand, may have any desired shape, but is preferably so constructed that it will render fairly easy its removal from the portion of the box structure into which it is inserted. For this purpose, the sides 13 and 14 of the box 10 are slotted at the folds or upper edges of such sides just sufficiently to permit the insertion of the main tab 42 by opening or distorting the same and also just sufficiently to permit the insertion of the auxiliary tab 43 at the other end of the member 40. There is thus produced the combined retaining and reenforcing means, generally designated by reference character 40'. This member will assist in securing the bathrobe in place and while giving the appearance of being a band completely surrounding the robe, will, in fact, extend over only one side of the same. It will thus serve in place of such a band, while serving the additional functions of reenforcing the box and retaining the robe 30 securely in place. The auxiliary retaining and securing means is made of a blank 50, comprising the intermediate or web portion 51 having the end tabs 52 and 53. The end tab 52 may have any desired form, but is preferably so arranged as to render it relatively difficult to remove from the box. Similarly the end tab 53, on the other hand, while it may have any desired form, is preferably so arranged, as to render its removal relatively easy. The tabs 52 and 53 are inserted through appropriate slots in the tops or folded edges of the end 15 and the partition 20 of the box 10. There is thus provided the combined retaining and reenforcing means, generally designated by reference character 50' and serving to retain the slippers 60 in place. In appearance, the member 50' would appear to surround the slippers. In fact, however, it extends over one side only of the slippers, thus serving the additional functions of reenforcing the portion 12 of the box and retaining the slippers in place.

This completes the description of the construction of the aforesaid illustrative embodiment of the devices of the present invention. It will be noted that such devices are simple in construction and may be easily, conveniently and economically fabricated and assembled. In use, the box lends itself ideally to the proper containing and retention of a bathrobe or slippers or combination of bathrobe and slippers for transportation and display. The main and auxiliary combined retaining and reenforcing means not only serve the purposes indicated, but also give the appearance of surrounding, in the form of bands, the bathrobe and slippers, respectively, with which they are

associated. Other superiorities and advantages of the devices of the present invention, particularly as exemplified in the aforesaid illustrative embodiment of the same, will readily occur to those skilled in the art to which the present invention relates. 70

What I claim as my invention is:

1. A box or like container for bathrobes, bathrobe and slippers combinations, and the like, comprising, in combination, a receptacle having side walls, and a combined retaining and reenforcing member spanning said receptacle and having a tab at each end passing into a corresponding side wall of said receptacle, the tab at one end of said combined retaining and reenforcing member being more readily insertible and removable than the tab at the other end of said combined retaining and reenforcing member. 75

2. A box or like container for bathrobes, bathrobe and slippers combinations, and the like, comprising, in combination, a receptacle having side walls, and a combined retaining and reenforcing member spanning said receptacle and having a tab at each end retained by a corresponding side wall of said receptacle, the tab at one end of said combined retaining and reenforcing member being more readily insertible and removable than the tab at the other end of said combined retaining and reenforcing member. 80

3. A box or like container for bathrobes, bathrobe and slippers combinations, and the like, comprising, in combination, a receptacle having folded side walls, the folds of which are at their outer edges, and a combined retaining and reenforcing member spanning said receptacle and having a tab at each end passing into a corresponding side wall of said receptacle, the tab at one end of said combined retaining and reenforcing member being more readily insertible and removable than the tab at the other end of said combined retaining and reenforcing member. 100

4. A box or like container for bathrobes, bathrobe and slippers combinations, and the like, comprising, in combination, a receptacle having folded side walls, the folds of which are at their outer edges, and a combined retaining and reenforcing member spanning said receptacle and having a tab at each end retained by a corresponding side wall of said receptacle, the tab at one end of said combined retaining and reenforcing member being more readily insertible and removable than the tab at the other end of said combined retaining and reenforcing member. 110

5. A box or like container for bathrobes, bathrobe and slippers combinations, and the like, comprising, in combination, a receptacle having side walls, and a transversely disposed partition member dividing said re- 120

130

5 receptacle into a main bathrobe portion and an auxiliary slippers portion, and a combined retaining and reenforcing member spanning said auxiliary slippers portion of said receptacle and having a tab at each end retained by an end wall of said receptacle and by said partition member.

6. A box or like container for bathrobes, bathrobe and slippers combinations, and the like, comprising, in combination, a receptacle having folded side walls, the folds of which are at their outer edges, and a transversely disposed partition member dividing said receptacle into a main bathrobe portion 10 and an auxiliary slippers portion, and a combined retaining and reenforcing member spanning said auxiliary slippers portion of said receptacle and having a tab at each end retained by an end wall of said receptacle 15 and by said partition member.

20 7. A box or like container for bathrobes, bathrobe and slippers combinations, and the like, comprising, in combination, a receptacle having side walls, a transversely disposed partition member dividing said receptacle 25 into a main bathrobe portion and an auxiliary slippers portion, and a plurality of combined retaining and reenforcing members one spanning said main bathrobe portion 30 of said receptacle and having a tab at each end retained by a corresponding side wall of said receptacle and the other spanning said auxiliary slippers portion of said receptacle and having a tab at each end retained by an end wall of said receptacle and by said partition member.

35 8. A box or like container for bathrobes, bathrobe and slippers combinations, and the like, comprising, in combination, a receptacle having folded side walls, the folds of which are at their outer edges, a transversely disposed partition member dividing said receptacle into a main bathrobe portion and an auxiliary slippers portion, and a plurality 40 of combined retaining and reenforcing members one spanning said main bathrobe portion of said receptacle and having a tab at each end retained by a corresponding side wall of said receptacle and retained between the folds of said side wall and the other spanning said auxiliary slippers portion of said receptacle and having a tab at each end retained by an end wall of said receptacle and by said partition member.

45 9. A box or like container for bathrobes, bathrobe and slippers combinations, and the like, comprising, in combination, a receptacle having folded side walls, the folds of which are at their outer edges, a transversely 50 disposed partition member dividing said receptacle into a main bathrobe portion and an auxiliary slippers portion, and a plurality of combined retaining and reenforcing members one spanning said main bathrobe portion 55 of said receptacle and having a tab at

each end passing into a corresponding side wall of said receptacle and retained between the folds of said side wall, the tab at one end of said combined retaining and reenforcing member being more readily insertible and removable than the tab at the other end of 70 said combined retaining and reenforcing member and the other spanning said auxiliary slippers portion of said receptacle and having a tab at each end retained by an end wall of said receptacle and by said partition 75 member.

In testimony whereof, I have signed my name to this specification this 11th day of April, 1928.
